(57) **CLAIM**

The ornamental design for a tubo spot light, as shown and described.

DESCRIPTION

FIG. 1 is a bottom perspective view of a tubo spot light according to our new design;

FIG. 2 is a top perspective view thereof;

FIG. 3 is a right side view thereof taken along line 3-3 of FIG. 5;

FIG. 4 is a front view thereof taken along line 4-4 of FIG. 5;

FIG. 5 is a bottom plan view thereof; and,

FIG. 6 is a top plan view thereof.

The dash-dash broken lines illustrate environmental structure and form no part of the claimed design.
